US00D609814S

(12) **United States Design Patent**
Banryu

(10) **Patent No.:** **US D609,814 S**
(45) **Date of Patent:** **** Feb. 9, 2010**

(54) **CONNECTOR FOR ULTRASONIC PROBE**

(75) Inventor: **Atsunobu Banryu**, Funabashi (JP)

(73) Assignees: **Kabushiki Kaisha Toshiba** (JP);
Toshiba Medical Systems Corporation
(JP)

(**) Term: **14 Years**

(21) Appl. No.: **29/334,664**

(22) Filed: **Mar. 31, 2009**

(30) **Foreign Application Priority Data**

Nov. 28, 2008 (JP) 2008-030511

(51) **LOC (9) Cl.** **24-01**

(52) **U.S. Cl.** **D24/187**

(57) **CLAIM**

The ornamental design for a connector for ultrasonic probe, as shown and described.

DESCRIPTION

FIG. 1 is a front, top and left side perspective of a connector for ultrasonic probe, showing my new design;

FIG. 2 is a front elevational view thereof; the opposite side being a mirror image thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines shown are included for the purpose of illustrating portions of the connector for ultrasonic probe that form no part of the claimed design.
